UNITED STATES PATENT OFFICE.

HUGO SCHISSEL, OF INDIANAPOLIS, INDIANA.

METHOD AND APPARATUS FOR PRODUCING CONCRETE STRUCTURES.

Application filed August 15, 1921. Serial No. 492,294.

To all whom it may concern:

Be it known that I, HUGO SCHISSEL, a citizen of the United States, residing at Indianapolis, in the county of Marion and State of Indiana, have invented certain new and useful Improvements in Methods and Apparatus for Producing Concrete Structures, of which the following is a specification.

10 This invention relates to concrete construction, such as the building of houses, bridges and the like, and the primary object of the invention is to provide an improved method and apparatus for facilitating the building of concrete walls, floors and the like, by which the use of the ordinary wooden forms or moulds is dispensed with, thereby resulting in a material saving of time and labor incident to the building of 15 and the knocking down of the wooden forms and the saving of the cost of such forms.

Another object of the invention is to provide an improved means for building concrete walls, floors and the like, embodying 20 a supporting knock down structure, which can be readily used again and again, and removable bridging plates carried by the supporting structure for receiving the concrete when the same is poured, the device 25 also including novelly arranged pre-cast concrete slabs, which are adapted to be associated with the bridging plates to bridge the 30 gaps therebetween, and to strengthen the concrete structure being formed, said pre-cast slabs being adapted to be formed integral 35 with the concrete structure after the structure is set and to form means for spacing the braces or other reinforcing steel and holding the same above the bridging plates 40 in order to permit the reinforcing steel to be wholly embedded within the concrete structure.

A further object of the invention is the provision of novel metallic bridging plates 45 for use with the supporting structure, and a novel means for supporting the plates, whereby the plates can be readily removed without necessitating the removal of the entire supporting structure, so as to permit the plates to be readily used again, while the concrete construction just moulded is 50 drying out.

A further object of the invention is the provision of the novel precast slabs for overlying the margins of the metallic bridging plates and the supporting structure, said

slabs also forming means for permitting the ready attachment of electric outlet plugs in position.

A further object of the invention is the provision of novel precast concrete pillar constructions for association with the plates and supporting structure, and a novel means for truing the precast pillar constructions in position, said pillar constructions 60 permitting concrete pillars or columns to be readily formed at the same time the floor or other structure is being formed.

A further object of the invention is the provision of a novel means for holding the caps of the precast pillar constructions in place, while the pillars or columns are being made.

A still further object of the invention is the provision of a novel supporting structure 75 for holding the bridging or moulding plates in position during the forming of walls, and novel members for holding the bridging or moulding plates in spaced relation so that a wall of uniform thickness can be readily 80 made, said spacing members being of concrete or cement, precast and adapted to remain in a wall after the same has been formed, said members also having wedges 85 associated therewith for permitting the bridging or moulding plates to be brought into firm contact with said spacing members.

With these and other objects in view, the invention consists in the novel construction, 90 arrangement and formation of parts, as will be hereinafter more specifically described, claimed and illustrated in the accompanying drawings, forming a part of this specification, in which drawings:

Figure 1 is a plan view of the apparatus in position for moulding a floor or the like, illustrating the novel means for associating the precast pillar forms therewith.

Figure 2 is a longitudinal section through the apparatus for forming concrete floors and pillars taken on the line 2-2 of Figure 1.

Figure 3 is a transverse section taken at right angles to Figure 2 illustrating the means of forming concrete floors and pillars taken on the line 3-3 of Figure 1.

Figure 4 is an enlarged fragmentary plan view illustrating the means of associating the precast pillar forms, and the precast pillar cap plates with the other parts of the apparatus.

Figure 5 is an enlarged fragmentary vertical section, taken on the line 5—5 of Figure 4.

Figure 6 is an enlarged fragmentary vertical section, taken at right angles to Figure 5 on the line 6—6 of Figure 4.

Figure 7 is a detail fragmentary plan view of a portion of the apparatus utilized for forming low or foundation walls and partition walls.

Figure 8 is a vertical section through the means of forming foundation walls, taken on the line 8—8 of Figure 7.

Figure 9 is a fragmentary side elevation of the apparatus for forming story walls and the like.

Figure 10 is a detail sectional view of a portion of the apparatus used for wall construction, showing the use of the precast concrete spacers taken on the line 10—10 of Figure 9.

Figure 11 is a vertical transverse section through the same taken on the line 11—11 of Figure 9 showing a part of the concrete wall already formed.

Figure 12 is a fragmentary vertical section through the apparatus, taken on the line 12—12 of Figure 10, illustrating the use of the precast spacers.

Figure 13 is a fragmentary plan view of a portion of the apparatus used for story wall construction.

Figure 14 is an enlarged fragmentary vertical sectional view through a portion of the apparatus used for building floors and the like, and illustrating another form of precast pillar mould for use therewith.

Figure 15 is a diametric section through the pillar form taken on the line 15—15 of Figure 14.

Figure 16 is an enlarged detail fragmentary side elevation of a portion of the moulding member for use in connection with the portions of the precast pillar moulds or forms.

Referring to the drawings in detail, wherein similar reference characters designate corresponding parts throughout the several views, the letter A indicates the apparatus used for floor construction and the like, which as shown includes the under supporting structure B, the mold plates C, the precast bridging slabs D, the precast pillar forms E, and the precast pillar form caps F.

The supporting understructure B will be manufactured in standard units or pieces and of various sizes to fit the given conditions for any building, and as shown includes the supporting posts or standards 20. These posts or standards are of course, formed of wood and the like, and support the longitudinally extending stringers 21, which are also formed of wood. The stringers 21 are held in place on the upper ends of the posts or standards 20 by means of

suitable cleats 22, which are secured to opposite sides of the posts, as clearly shown in Figures 2 and 3 of the drawings. The lower ends of the posts 20 can be supported by suitable bases 24, which may consist of pairs of wedge plates 25, whereby the height of the posts 20 can be regulated within certain limits to suit varying conditions. The posts 20 can be further braced, in order to prevent accidental slipping thereof by means of longitudinally and transversely extending bracing strips 26 and 27'. The stringers 21 are provided at certain spaced points with openings for the reception of removable pins or rods 27, which are adapted to project equi-distantly beyond the opposite side faces of the stringers and serve as means for detachably supporting the sub-stringers 28, which can be made in any desired length. It is to be noted at this point, that the sub-stringers 28 end below the upper ends of the main stringers 21 and form supports for holding the bridge or mould plates C, which will now be described.

The mould plates C can be made in various standard sizes and are preferably formed of metal, and each includes a frame 29 formed of channel iron, which supports an outer wall 30 that can be spot welded there-to if so desired. These outer walls 30 are braced at predetermined spaced points by strap iron or the like 31, which extend across the plates. As stated, the mould plates C are adapted to be positioned on the sub-stringers 28 and may terminate substantially flush with the upper surface of the main stringers 21 and are arranged on opposite sides of the stringers in close relation to each other, as clearly shown in Figure 1 of the drawings.

The precast slabs D also can be formed in various standard sizes and are adapted to be placed over and to rest upon the upper surface of the main stringers 21 and the side edges of the mould plates C as clearly shown in Figures 1 and 3 of the drawings. It is desirable, that these precast slabs D have substantially semi-circular indentations 32 formed in their terminals. These indentations 32 form circular openings when the slabs are placed end to end, which are of a sufficient diameter to receive a standard size of electric outlet box. If the outlet boxes are not placed in position at the time of moulding, the precast slabs D can be held against lateral movement by suitable finishing nails, (not shown) which can be driven into the main stringers into frictional engagement with the edges of the semi-circular recesses 32.

The use of the precast pillar forms E and the precast pillar cap plates F form an important part of the invention, and these precast pillar forms may be of different forms.

as shown in Figures 2 and 3 of the drawings and in Figures 14 to 16 of the drawings. These precast pillar forms E as shown in Figures 2 and 3 of the drawings include a 5 concrete or cement shell 35, and a flared hollow cap portion 36. The shaft 35 and the cap 36 are of sufficient thickness to withstand internal pressure caused by inflowing concrete. The outer edge of the flared cup 10 36 may be rabbeted as at 37, for the reception of the inner edges of the cap precast plates F, which will be hereinafter more fully described. The column or pillar forms shown in Figures 14 to 16 inclusive and 15 designated by the letter G have been found to be the most desirable in actual practice, as when the entire shaft 35 is precast the same is liable to become broken or injured during the transmission or while the same 20 was being set in position. In view of this the precast column or pillar form G includes the top sections 38 having the hollow relatively short shaft portion 39 and the flared cap 40 and a base section 41. This 25 base section is of hollow formation and is adapted to be aligned with the upper section 38. These two sections 38 and 41 are connected by a metallic mould member 42. This mould member 42 can be made of two 30 or more sections according to the size column or pillar being formed. As shown the metallic mould member 42 includes a pair of semi-circular portions 43, the meeting edges of which carry angle brace strips 44. 35 These angle brace strips 44 are provided with aligned inwardly extending notches 45, which are adapted to receive connecting bolts 46. The connecting bolts 46 have threaded on the same nuts 47. If desirable 40 wedge members 48 can be driven in between the nuts 47 and the angle strips 44, in order to assure bringing the sections 43 into intimate engagement with one another.

The upper section 38 can be first placed 45 in position and hung from a removable beam 49, which can be placed either over the mould plates C or over the stringers 21. The supporting beam section 49 has twisted around the same depending wires 50, the 50 lower portions of which are connected to pins 51, secured to the relatively short shaft section 39 of the upper portion 38. This provides a convenient means for holding the upper sections 38 of the column or pillar 55 forms in position. When the upper and lower portions 38 and 41 are placed in position, the metallic mould section 42 is placed around the same and concrete is then poured into the mould up to the flared portion of the upper section 38, after which the supporting beam 49 is removed. The wires 50 can be broken or twisted off if so desired. 60 This will hold the upper section 38 in position, until the other parts of the structure 65 have been poured.

It has been found that the column or pillar forms cannot be sometimes placed in the exact position, and in order to align the forms the means H has been provided. This means H for aligning the pillar or column forms may consist of wedge members 52, which can be placed intermediate the mould plates C and the column cap or head 36 or 40, as the case may be and between the stringers 21 and the cap or head. 70 If so desired, spacing plates 53 can be placed between the wedges and the mould plates C or the stringers 21. By this construction, it can be seen that it is merely necessary to tap the wedges 52 in order to properly align 75 the pillar or column forms.

The method pursued in making an ordinary slab floor and supporting columns will be to place the posts 20 and the stringers 21 in position as heretofore described, and 80 then arrange the precast columns or pillar forms at the desired points and in the desired formation. The substringers 28 will then be placed in position and the bridge plate C laid on the same. The meeting 85 edges of the mould plates C will be bridged by means of the precast slabs D which will also cover the stringers 21. The column or pillar forms can then be aligned by means of wedges 52 as described, and the pillar 90 cap plate F placed in position, which will now be described. These pillar cap plates F are also formed of cement or the like, and consist of sections 54, which have their inner edges shaped to conform to the configuration of the column caps with which they are to be associated. These inner edges rest upon the rabbeted portions 37 of the column caps 36 and upon the upper surface 95 of the mold plates C. The bridge plates D can then be placed in abutting relation with the plate F whenever these plates may come together. If desirable, upstanding pins 55 can be embedded in the plates F at the time 100 of their casting so that uniting wires 56 can be twined around the same in order to hold the plates in position against movement. After the apparatus has been set up as described, the concrete is poured thereon in the usual manner, and it will be seen that the same will flow into the precast pillar or 105 column forms E and over the mould plates C and the precast slabs D and the precast cap plates F. After the concrete has been 110 poured, the same is left to set for a predetermined length of time, after which the stringers 28 are removed and the plates C taken down. The other parts of the supporting structure B, namely the posts 20 and the main stringers 21 are left in position until the concrete structure has thoroughly 115 dried. It can be seen that the plates C and substringers 28 and the supporting rods 27 can be used while this concrete structure is 120 drying out. It is to be noted that the precast 125 plates F are not to be removed until the concrete has set. 130

slabs D and the plates F form an integral part of the concrete structure after the same has been formed, and these slabs D form a convenient means for spacing the reinforcing members from the mould plates C, so that the concrete can flow entirely around the same, thereby insuring the thorough fire-proofing of the structure.

In the building of low or foundation walls or partition walls, the necessity of a supporting structure is superfluous, and the plates are merely placed upon one another. This is clearly shown in Figures 7 and 8 of the drawings. For clearness the mould plates in Figures 7 and 8 have been designated by the numeral 60. As stated, the plates 60 are placed one upon the other and held in spaced relation by means of precast concrete spacer members 61. These precast spacers 61 have cast therein relatively thin metallic strips 62 which project outwardly from the precast spacers 61. These strips 62 are adapted to be positioned between the mould plates C, and owing to the relative thinness thereof, the same will not space the plates a sufficient distance to permit the escaping of concrete therebetween. These metallic strips are provided with openings for the reception of wedges 63, and it can be seen that it is merely necessary to drive the wedges into position in the metallic strip 62 in order to force the mould plates 60 into intimate engagement with the cement spacers 61, in order to insure of a wall of uniform thickness being formed. In the making of corners, a precast cement angle 64 can be utilized and this corner casting is held against displacement by means of two of the precast spacers 61 which are placed at the terminals thereof. After the plates 60 have been placed in position, the concrete is then poured between the same, and after the same has set the plates can be readily removed.

In the building of story walls, practically the same apparatus is used as that for the building of slab floors, and the mould plates are held in place in the same manner.

As shown, outside upright stringers 65 are provided and inside upright stringers 66. The inside stringers 66 rest upon the upper surface of the formed slab floor, which is designated by the numeral 67. The inside vertical stringers 66 extend above the upper surface of the outside stringers 65, and these stringers are connected together in spaced relation by means of relatively short supporting braces 68, which form supports for the longitudinally extending bracing beams 69. The lower ends of the outside stringers 65 have connected thereto a longitudinally extending bracing beam 70, which is adapted to rest upon relatively short supporting beams 71, which are secured to the stringers 65. This apparatus is so constructed as to eliminate

the use of the usual heavy compression members and merely necessitates the use of light tension members, acting against each other. A lower horizontal tension member 72 is connected to the longitudinally extending beam 70 and to a stationary part of the building, such as one of the columns designated by the numeral 73 which has been previously formed. As shown a collar 74 is utilized for connecting the rod 72 with the column. An upper diagonal tension rod 75 is provided, and its lower end is anchored as at 76 to the slab floor 67 at a convenient point, and its upper end is connected to the longitudinally extending upper beam 69. The tension members 72 and 75 have interposed therein turn buckles 77, so that the active length thereof can be adjusted for a purpose, which will be hereinafter more fully described. The inside stringers secure the structure vertically and the rods 72 and 75 by pulling the outside stringers 65 against the slab 67 already cast support the apparatus horizontally. The apparatus is plumbed by simply loosening the rods 75 and tightening the rods 72 or vice versa. Bridge plates 80 are used in this construction and these bridge plates are exactly the same as the bridge plates utilized in the floor construction. The plates 80 are placed one upon the other and are held against accidental displacement by means of removable bolts or rods 81, which are the same as the rods 27 utilized in the apparatus for forming the slab floor. The mould plates 80 are held against collapsing and in a preferred spaced relation by means of precast spacers 82, which are the same as the precast spacers 61 used in the low wall construction. These present spacer plates 82 also carry their plates 83, which are adapted to receive the wedge members 84 for bringing the mould plates 80 into firm engagement with the precast spacer plates 82. After the mould plates 80 have been placed in position the concrete is then poured between the same in the ordinary manner. After the wall has been formed, the second slab floor can be erected.

In the forming of story walls, precast cement corner members 64 are utilized the same as is shown in Figure 7 of the drawings. In the forming of windows and the like, precast channel sections 85 can be used and held in place by cement spacers 82 as clearly shown in Figure 10 of the drawings. The cement spacer blocks 82 perform the dual function of a tie and as a spacer for insuring the proper thickness of the wall. After the removal of the plates 80, the flat steel bars 83 can be readily twisted off or left in place on the outside of the building to be used as an anchor for a brick veneer construction.

It is to be also noted that precast cement

slabs 86, the same as the slabs D as used in the floor construction, are placed over the series of plates 80 as clearly shown in Figures 10 and 12 of the drawings.

5 From the foregoing description, it can be seen that an exceptionally simple method and apparatus has been provided, for forming concrete structures, without necessitating the use of the heavy and cumbersome 10 wooden moulds as now used, and which merely embodies light supporting under-structures which can be readily reused and reusable mould plates and precast cement members, which are left in position to form 15 an integral part of the concrete structure after the same has set.

I claim:

1. The method of forming cementitious building structures consisting of building a 20 removable supporting stage, placing removable mould plates on the stage, placing precast cementitious slabs upon the plates to bridge the gaps therebetween, placing hollow cementitious precast pillar forms between certain of the plates, placing sectional 25 pillar cap precast plates upon the edges of the pillars and adjacent mould plates and then pouring concrete in the pillar forms and on the resultant structure.

30 2. The method of forming cementitious building structures consisting of building a removable supporting staging including spaced stringers removably supporting mould plates by and between the stringers 35 and below the lower surface thereof, placing relatively thin precast cementitious slabs upon the stringers and over the adjacent edges of the mould plates to bridge the spaces therebetween, placing precast hollow 40 pillar forms between certain of the mould plates, placing precast relatively thin cementitious pillar cap plates over the upper edges of the precast pillar forms and the adjacent mould plates, pouring concrete in the pillar 45 forms and over the mould plates and precast cap plates and slabs, and allowing the concrete structure to set a predetermined length of time, then removing the mould plates for allowing the concrete structure to thoroughly dry, and then removing the supporting casing.

50 3. An apparatus for forming cementitious building structures comprising a movable supporting staging including spaced stringers, substringers detachably carried by the opposite sides of the first mentioned stringers and disposed below the upper surface thereof, metallic mould plates disposed upon the substringers arranged substantially flush 55 with the upper surface of the first stringers, and precast slabs supported by the precast mould plates and arranged above the first mentioned stringers.

60 4. An apparatus for moulding cementitious building structures comprising a re-

movable supporting staging including spaced main stringers, removable pins carried by the main stringers, removable substringers positioned upon the pins, metallic mould plates placed upon the substringers, precast 70 cementitious slabs disposed upon the main stringers and over the adjacent edges of the metallic mould plate, said precast cementitious slabs being adapted to form an integral part of the cementitious structure as the 75 same is moulded.

5. An apparatus for forming cementitious building structures comprising a removable supporting staging including main stringers, substringers detachably supported by the 80 main stringers, major mould removable plates laid upon the substringers, and removable precast minor mould members disposed above the stringers and over the adjacent edges of the major removable mould 85 plates to bridge the spaces therebetween.

6. An apparatus for building cementitious structures comprising a removable supporting staging including spaced main stringers, substringers detachably supported by the 90 side faces of the main stringers and arranged below the upper faces thereof, major removable mould sections disposed upon the substringers, the upper faces of the major metallic mould sections being substantially 95 flush with the main stringers, and precast elongated substantially rectangularly shaped cementitious minor mould plates arranged over the main stringers and disposed upon the adjacent edges of the major removable 100 mould sections to bridge the spaces therebetween, to prevent the escape of cementitious material over the supporting staging.

7. An apparatus for forming cementitious building structures comprising a supporting 105 staging, major metallic removable mould sections supported by the staging, precast hollow cementitious pillar forms disposed between certain of the major metallic mould sections, and precast cementitious pillar cap plates disposed upon the adjacent edges of the precast cementitious pillar forms and the major mould plates.

8. An apparatus for forming cementitious building structures comprising a removable 115 supporting staging, major metallic mould members detachably supported by the staging, precast cementitious minor mould plates placed upon the major mould plates to bridge the spaces therebetween, precast cementitious pillar forms disposed between certain of the plates, wedge members disposed between the pillar forms and the plates to facilitate aligning of the pillar forms in relation to the plates, and precast cementitious pillar cap slabs disposed over the adjacent edges of the pillar forms and the major mould sections.

9. An apparatus for forming cementitious building structures comprising a supporting 130

- staging including supporting posts, stringers carried by the supporting posts, means for bracing the supporting posts, the stringers having formed therein intermediate their 5 upper and lower faces a plurality of openings, supporting pins detachably fitted in the openings, substringers disposed upon the pins, and major mould plates disposed upon the substringers and having their upper faces arranged substantially flush with the upper surfaces of the main stringers.
10. An apparatus for moulding cementitious building structures comprising a removable supporting stage including spaced parallel main stringers, removable pins carried by the stringers and arranged to extend beyond the opposite side faces thereof, substringers detachably fitted upon said pins, spaced metallic mould plates detachably fitted upon the substringers having their upper faces disposed substantially flush with the upper edges of the main stringers, minor precast mould plates arranged over the stringers and the adjacent edges of the 20 mould plates, precast cementitious hollow pillar forms disposed between certain of the major mould plates, wedge members disposed between the hollow pillar form and certain of the main stringers and certain of the major mould plates for aligning the pillar forms and precast pillar cap plates disposed upon the upper edges of the pillar forms and upon the adjacent major mould plates.
- 25 11. In an apparatus for moulding cementitious building structures, a precast cementitious hollow pillar form including a hollow flared cap and a hollow cylindrical body.
- 30 12. A device for forming cementitious pillars comprising an upper section including

a hollow cementitious precast body, a lower section including a hollow precast cementitious body and a removable metallic mould section disposed between and engaging the upper and lower sections. 45

13. A device for forming cementitious pillars comprising an upper section including a hollow flared cementitious cap and a cylindrical hollow cementitious body, a lower section including a hollow cylindrical body, and a metallic intermediate mould section including a plurality of arcuate plates arranged to engage about the upper and lower sections, and means for connecting the metallic mould sections together. 50

14. A device for forming cementitious pillars comprising an upper section including a hollow flared cementitious cap and a cylindrical hollow cementitious body, a lower section including a hollow cylindrical body, and a metallic intermediate mould section including a plurality of arcuate plates arranged to engage about the upper and lower sections, means for connecting the metallic mould sections together, said means including nuts and bolts detachably carried by the mould sections and wedge members arranged to engage the mould sections and the nuts. 60 65

15. The method of forming cementitious pillars consisting of hanging a hollow cementitious head in position, aligning a hollow cementitious base with the head, placing a removable mould section about the head and base, pouring concrete into the base, mould section and a portion of the head, removing the supporting means for the head and then pouring concrete in the other portion of the head. 70 75

HUGO SCHISSEL
